UNITED STATES PATENT OFFICE

CHARLES F. BONHACK, OF NEW YORK, N. Y.

MACHINE FOR UNLOADING FRICTION-MATCHES AFTER DRYING.

SPECIFICATION forming part of Letters Patent No. 254,191, dated February 28, 1882.

Application filed December 12, 1881. (No model.)

To all whom it may concern:

Be it known that I, CHARLES F. BONHACK, of the city, county, and State of New York, have invented certain new and useful Improvements in Machines for Unloading Friction-Matches, of which the following is a specification.

This invention relates to an improved machine for unloading friction-matches after they have been dried and depositing them in regular numbers on shelves, so that they can be conveniently removed and packed into the boxes for shipment.

The invention consists of a guided follower, to which the "setter" that contains the finished matches is applied, said follower and setter being moved in horizontal direction by suitable mechanism, so as to force the bunch, with the completed matches sticking out therefrom, against a vertical stop-frame having horizontal partitions, and push them the matches by the push-pins of the setter out of the bunch and along the partitions of the stop-frame onto a series of horizontal unloading-shelves, from which they are successively removed and placed into the boxes. When the bunch has been moved up to the stop-frame the perforated guide-plate of the setter is locked thereto by means of hinged latch-pieces to the vertical stop-frame, so that the push-pins may be withdrawn from the bunch, which is then removed from the apparatus, either to be used over again for setting sticks or for being recharged, as required.

In the accompanying drawings, Figure 1 represents a side elevation, partly in section, of my improved machine for unloading friction-matches. Fig. 2 is a plan view of the same with parts broken away. Fig. 3 is a vertical transverse section on line $x-x$, Fig. 2. Fig. 4 is a detail perspective view of a clamp for locking the guide-board of the setter to the top piece of the stop-frame, and Fig. 5 is a perspective view of a bunch of match-sticks, shown detached from the setter to more clearly illustrate the partly-displaced projecting matches which are ready to be entirely pushed out of the bunch by the operation of this machine.

Similar letters of reference indicate corresponding parts.

Referring to the drawings, A represents the

supporting-frame of my improved machine for unloading friction-matches after they have been set, dipped, and dried. The supporting-frame A serves to guide in horizontal top and bottom ways, A' A², a vertical follower, B, which is moved forward in a horizontal direction by means of an actuating screw, lever, or other suitable mechanism. The setter F is applied by a dovetailed head into a dovetailed recess of the follower B, the setter being provided with a number of push-pins, f, and a perforated guide-board, F'. The push-pins are attached to the head of the setter and arranged in rows and equidistantly from each other, as will appear more fully from a separate application for a machine for setting match-sticks, which has been filed at the same date herewith.

The setter F carries the push-pins f, that take against the ends of some of the displaced matches, still retained in, but not entirely pushed through, the bunch of match-sticks D, which are securely held together by means of a strong rubber band, D'. By the setting-machine a series of sticks have been partly pushed out of the bunch, and then finished by dipping and drying while remaining in the setter. The finished matches project from the end of the bunch D, as shown in Figs. 1 and 5, and are ready to be entirely pushed out of the bunch by the forward motion of the follower and setter.

The setter F is guided by means of corner-recesses on the horizontal ways A' A² of the frame A, its top piece being provided with hinged side pieces, F², which during the setting of the sticks have been placed in position against the perforated side board, F', but which are now thrown back to be out of the way when the setter, with the finished matches, is applied to the follower of the unloading-machine, as shown in Fig. 1. When the bunch D has been moved forward with the setter F until the rows of matches enter into the spaces between the horizontal partitions of a vertical stop-frame, C, and the bunch abuts against said stop-frame, as shown in Fig. 2, the perforated guide-board F' is locked at the lower end by means of pins, spring-catches or other devices, a, and at the upper end by means of a detachable clamp, shown in dotted lines in Fig. 1, and in perspective view in Fig. 4, or, preferably, by means of

hinged latches E, arranged at the top of the stop-frame C, as shown in Figs. 1 and 2. The motion of the follower and setter is then continued until the matches have been pushed entirely through the bunch and beyond the partitions of the stop-frame and deposited on horizontal shelves D², which are supported in a removable manner in vertical side standards, D³, of the frame A. From the shelves the matches are removed directly into the boxes, which, when one hundred push-pins are used in each row of the setter, would push out and deposit one hundred matches upon each shelf D², so that consequently the same number of matches is placed in a very convenient manner into each box. As soon as this is accomplished the follower is moved in backward direction and the push-pins withdrawn entirely from the bunch, during which motion the bunch D and the perforated guide-board F' are firmly retained in position by the latches E and locking devices a, as shown in Figs. 2 and 3, until the push-pins are withdrawn entirely from the bunch. The latches E and locking devices a are then removed from the perforated guide-board F', and the bunch and the setter removed from the machine, to be returned to the setting-machine for renewed setting of the sticks. In this manner the machine for unloading the matches works in connection with the machine for setting the match-sticks, it simply complet-

ing the operation which has been begun in the setting-machine, so as to carry out the system of finishing single matches at a considerable saving in time and labor, and without the loss of stock and danger of accident occurring in the system of making matches from double sticks heretofore in general use.

Having thus described my invention, I claim as new and desire to secure by Letters Patent—

1. A machine for unloading friction-matches, consisting of a horizontally-movable follower, of a setter applied thereto and holding the bunch with the set and finished matches, of a stop-frame having horizontal partitions, and of removable horizontal unloading - shelves, all substantially as and for the purpose set forth.

2. The combination, in a machine for unloading matches, of a guided setter having push-pins and a perforated guide-board with locking devices applied to the upper and lower parts of the guide - board so as to retain the same and the bunch for withdrawing the push-pins from the latter, substantially as set forth.

In testimony that I claim the foregoing as my invention I have signed my name in presence of two subscribing witnesses.

CHARLES F. BONHACK.
